UNITED STATES PATENT OFFICE.

ALBERT H. DE GASTON AND FREDERIC McLEAN, OF SACRAMENTO, CALIFORNIA,
ASSIGNORS TO GLOBE IRON WORKS, OF SACRAMENTO, CALIFORNIA, A CORPOR-
ATION OF CALIFORNIA.

INTERNAL-COMBUSTION ENGINE.

1,160,697.

Specification of Letters Patent. Patented Nov. 16, 1915.

Application filed July 7, 1913. Serial No. 777,612.

To all whom it may concern:

Be it known that we, ALBERT H. DE GASTON, a citizen of the United States, and FREDERIC McLEAN, a subject of Great Britain, residents of the city of Sacramento, county of Sacramento, State of California, have invented certain new and useful Improvements in Internal-Combustion Engines, of which the following is a specification.

The invention relates to internal combustion engines and particularly to an ignition device for internal combustion engines operating on oil fuel.

The object of the invention is to provide a quickly removable and attachable igniter.

Another object of the invention is to provide means for holding the portable igniter in place, which is so constructed that the igniter may be securely fastened in the cylinder or quickly removed.

With these and other objects in view, as will more fully hereinafter appear, the invention consists in certain novel features of construction and arrangement of parts, hereinafter fully described, illustrated in the accompanying drawings and particularly pointed out in the appended claims, it being understood that various changes in the form, proportions, size and minor details of the structures may be made without departing from the spirit of or sacrificing any of the advantages of the invention.

The invention is illustrated in the accompanying drawings, in which:

Figure 1 is a vertical cross section of the head end of the engine cylinder, showing the igniter of the present invention. Fig. 2 is a horizontal cross section of the head end of the engine cylinder showing the means of holding the igniter in place. Fig. 3 is an end view of the engine cylinder, partly broken away.

In internal combustion engines operating on oil fuel, ignition of the charge in the cylinder is often obtained by means of a heated igniter. It is evident that when the igniter is cold it is impossible to start the engine, and various means and methods have been heretofore employed for initially heating the igniter. When the igniter has become sufficiently heated to operate the engine on oil fuel, the auxiliary means of heat-

ing are disconnected or thrown out of operation and the heat of combustion in the cylinder is sufficient to maintain the igniter at the required temperature. The oil fuel is injected into the cylinder and onto the igniter where it becomes volatilized, and the heat of the cylinder walls and the igniter and the heat generated in compression is sufficient to ignite the charge.

In the present invention the igniter is readily removable from the cylinder, so that it may be heated to the required temperature at some external point, and inserted into the cylinder. It is evident that the means for securing the portable igniter in the cylinder must be capable of rapid manipulation, so that the igniter may be securely placed and the engine started before it cools.

In accordance with the present invention, the portable igniter 2 is arranged in the head 3 of the cylinder 4 in which operates the piston 5. The fuel injection nozzle 6 is arranged so that the charge of fuel is projected onto the tongue 7 of the igniter, which projects into the cylinder. The cylinder head is preferably formed with an inwardly flaring aperture 8 in which the igniter is arranged. The tongue of the igniter is of less diameter than the smaller end of the flaring aperture, and the igniter is provided with an annular shoulder 9 which engages the smaller end of the aperture. By forming the aperture larger in diameter than the tongue, any deposit or scale on the tongue will not interfere with the removal of the igniter. The igniter is formed with a head 11 of larger diameter than the shoulder 9, which bears against the outer surface of the cylinder head.

The igniter is detachably secured to the cylinder head by means of a screw 12 engaging in the bifurcated clamp 13. The clamp is provided with apertured bosses 14 at its opposite ends, through which pass the studs 15 which are screwed into the cylinder head. The clamp is held against the cylinder head by means of the nuts 16 engaging the studs. The aperture 17 in one end of the clamp is open at the side so that the nuts 16 may be released and the clamp swung about the other stud as a pivot to move the clamp out of its position in front

of the igniter. The screw 12 is provided with a handle 18 so that it may be readily turned to tighten or release the igniter. Secured to the portable igniter is an eye-bar 19 by which the igniter is held and carried when it is hot.

We claim:

1. In an internal combustion engine, a cylinder head having an inwardly flaring aperture therein, an igniter comprising an ignition tongue of lesser diameter than the aperture extending from said aperture into the cylinder, and a head of greater diameter than the small end of the aperture engaging the outer surface of the cylinder head and detachable means for holding the igniter in place with the head pressed against the cylinder head.
2. In an internal combustion engine, a cylinder head having an inwardly flaring

aperture therein, an igniter arranged in said aperture, said igniter comprising a head of larger diameter than the small end of the aperture and bearing against the outer surface of the cylinder head, a neck fitting 25 into the small end of the aperture and a tongue of smaller diameter than the aperture extending from the aperture into the cylinder and a clamp removably fixed to the cylinder head adapted to press the 30 igniter head against the cylinder head.

In testimony whereof, we have hereunto set our hands at Sacramento, California, this 20th day of June, 1913.

ALBERT H. DE GASTON.
FREDERIC McLEAN.

In the presence of—

FRANK F. CADLE,
H. G. PROST.
